UNITED STATES PATENT OFFICE.

OTTO VOLZ, OF BERLIN, GERMANY.

WATER-SOFTENING WASHING COMPOUND.

1,400,332.

Specification of Letters Patent. Patented Dec. 13, 1921.

No Drawing.

Application filed July 22, 1919. Serial No. 312,596.

To all whom it may concern:

Be it known that I, OTTO VOLZ, doctor of philosophy and technical chemist, residing at Berlin, in the State of Prussia, German Empire, have invented certain new and useful Improvement in a Water-Softening Washing Compound, (for which I have filed application in Germany, March 2, 1916,) of which the following is a specification.

10 The hardness of water is caused partly by its contents of sulfates and chlorids, partly by bicarbonates of earth-alkalis. The presence of the said salts renders the water pro rata of the quantity thereof contained un-
15 serviceable for washing purpose, as these salts bind large quantities of soap so that the latter is lost for its proper purpose, *i. e.* to serve as a washing and cleansing medium. As the insoluble lime and magnesia soaps,
20 formed when soap acts upon salts of the said kind, have no cleansing properties whatever, and even will tend to grease and stain the linen, the soap consumed by separating and decomposing the salts rendering the water
25 hard is not only absolutely wasted in the washing process, but the washing process itself is besides impeded by the earth alkali salts of the fatty acids deposited. For rem-
edying this evil it is the custom, not to men-
30 tion the special processes employed in and adapted for wholesale purposes only, such as the permutit process, to add, for house-
hold and other minor purposes, a suitable quantity of soda or the like to the washing
35 water or the soap, respectively. The object aimed at is, however, thereby only partly and imperfectly secured, as carbonates of alkalis will remove only the socalled permanent hardness of the water, *i. e.* will decom-
40 pose only the sulfates and chlorids of the earth alkalis and deposit them in form of carbonates, but will not destroy the socalled temporary hardness caused by the presence of bicarbonates of earth alkalis. The removal
45 of the latter will always still necessitate a corresponding quantity of soap, which also then is prematurely destroyed by the formation of insoluble earth-alkali salts of the fatty acids and lost as washing mediums. It
50 is possible to avoid this loss of soap by an addition of a corresponding quantity of caustic lime or caustic alkalis, but owing to the danger connected with their use it is not pos-
55 sible to employ them in a suitable manner in the household.

The present invention consists in this that, for removing the temporary hardness, *i. e.* the hardness caused by bicarbonates, instead of free caustic alkali starch or vegetable matter rich in starch and mixed to a medley 60 with caustic alkalis is added in a correspond-
ing quantity to the water to be softened, whereby by the intermediate formation of alkali carbonate simultaneously also a part 65 of the permanent hardness is destroyed. The remaining permanent hardness may, then, be removed in the usual manner by means of soda or the like. This may be either done simultaneously or subsequently. The said starch mixed with caustic alkali is 70 particularly adapted for removing the bicarbonates or the free carbonic acid in the water, because, if properly kept it will last for an indefinite time, may be conveniently and—because in a dry state it does not act 75 caustic—safely employed and is readily hy-
drolyzed in water, in particular in the presence of bicarbonates, whereby the bicarbonates are decomposed or the free carbonic acid is bound, respectively, and insoluble 80 moncarbonates are formed. Contrary to the known method of using, as an anti-boiler-
scales medium, alkalized cellulose or carbo-
hydrates mixed with carbonates or silicates of alkalis the use of starch moistened with 85 caustic alkali-lyes as a softener for washing and bathing water has the advantage that, on the one hand, water of any temperature may, within a short time, be fully softened by the caustic alkali liberated by the hydrol-
ysis, *i. e.* free from the permanent and also 90 from the temporary hardness, and, on the other hand, the starch solution remaining in the softened water will, by its slimy proper-
ties favoring the slipping of the parts, have 95 a general favorable influence on the washing process. The emulsioning capacity of vege-
table slimes with regard to dirt, oils and the like, and the protective effect of the smooth-
ening of the starch slime against friction are 100 generally known. The cellulose of the anti-
boiler-scales-preparation consisting of alka-
lized cellulose is not dissolved at all. It re-
mains as such in the precipitate so that there 105 are here no secondary effects favorable to the washing process, as will be produced by the dissolved starch.

A further advantage of the new water softening means consists therein that the starch prepared with caustic alkali-lye to a 110

mixture will, if kept in a normal manner, remain considerably longer non-decomposed and therefore remain effective as softening medium than alkalinized cellulose, because the latter does not form as intimate and uniform a combination with the caustic alkali as the starch, and practically absorbs it only.

If borax is added there will be formed 10 in the starch paste the salts of the ortho and meta boric acid not existing in solutions.

The partly saltlike binding of the caustic alkalis to the starch, or, in the example 15 given, to the starch and the borax removes the caustic effect of free, not bound caustic alkalis, which for use in the household and the like is both disagreeable and may under circumstances even be dangerous, and therefore renders a simple, safe manipulation by 20 women and servants and finally also a convenient dosaging, for example in form of cakes or briquets.

As hereinbefore stated the softening of 25 the water may be carried out at any temperature. The precipitation of the mono-carbonates of the earth alkali will be further favored by an addition of kaolin, talcum, fullers' earth (kieselguhr), chalk and 30 the like, substances which will have both an accelerating and absorbing effect; such additions further increase the durability of the softening medium. The removing of these insoluble materials together with the 35 precipitated earth alkali salts before using

the water may, if desirable, be obtained by settling or filtering, but, as a rule, it is not necessary.

By way of example, a suitable softening medium may be obtained by mixing 40

60 oz. potato flour,

16 oz. finest chalk,

20 oz. powdered kaolin or talcum,

52 oz. caustic soda lye of 42%,

20 oz. powdered borax,

32 oz. calcinated soda,

in a suitable manner, the potato flour and the borax binding the free alkali and forming a paste, which quickly hardens and may then be powdered or dosed by forming pastilles, cakes and such like. 50

For softening water $\frac{1}{4}$ oz. of the specified mixture is used for every 3 gallons of water and each degree of temporary hardness; it should, however, also be remembered that by this addition also about 2 degrees of permanent hardness will be removed. 55

I claim:

A water softening washing compound comprising approximately, by weight, 30 60 per cent. potato flour, 8 per cent. chalk, 10 per cent. powdered kaolin, 26 per cent. caustic soda, 10 per cent. powdered borax and 16 per cent. calcinated soda.

In testimony whereof I affix my signature 65 in presence of two witnesses.

DR. PHIL. OTTO VOLZ.

Witnesses:

LUCIE KRELLNBERG,
FRIEDA ROSENTHAL.
